United States Patent Office.

JOHN R. RICHARDS, OF MOUNT JOY, PENNSYLVANIA, ASSIGNOR TO HIMSELF AND ALFRED L. MENUEZ, OF CLEVELAND, OHIO.

Letters Patent No. 65,945, dated June 18, 1867.

IMPROVED SECTIONAL MOULDS FOR PUTTING UP BUILDINGS OF CONCRETE AND OTHER MATERIALS.

The Schedule referred to in these Letters Patent and making part of the same.

TO ALL WHOM IT MAY CONCERN:

Be it known that I, JOHN R. RICHARDS, of Mount Joy, in the county of Lancaster, and State of Pennsylvania, have invented a new combination and means of hardening, by the intervention of certain sectional moulds a Composition for Forming Artificial Stone for Building Purposes, (of dwelling-houses, walls, &c.;) and I do hereby declare that the following is a full and exact description of the construction and application of my flanged sectional moulds and process of hardening the composition I employ, reference being had to the accompanying drawings, making a part of this specification, in which—

Figure 1 is a perspective view of a portion of my sectional moulds united for the inner and outer face of the wall, representing two stories.

Figure 2 is a perspective view of one of the inner sections, H², and its counterpart or outer section, B².

Figure 3 shows a side elevation of the same, with the lower sections A² and I² added.

Figure 4 is a front view, showing the spaces for the joists.

Figure 5, the joists shown with dove-tail ends, by which they are embedded into the compost forming the walls.

Figure 6 represents four walls put up, with the sectional moulds removed.

The object of this invention is to provide a series of moulds, in sections, united by flanges, so arranged as to break joints alternately with the window and door-frames, sills, casing, and cornice, and any desired moulding or ornamental carving raised or depressed in the patterns forming the moulds, between which the composition is firmly packed and then hardened. These sections are built up from the foundation, forming the inner and external cast of the walls of any desired thickness, so bound together by the beams and joists as to make the four walls, (with window and door-spaces all in place,) of one continuous stone-like material, firmly set, and ready for roofing. These moulds will answer for any number of dwellings of the same size and pattern. For a different design another series or portions of a series of moulds must be provided.

The sections are formed as shown by fig. 2. In their arrangement B² shows a flange, F, above and below, with holes for bolts, fastened by a nut and screw to the section above and below. X shows a box surrounding the window, as wide as the wall shall be thick. y forms the outer projection of the window, and z the sill, carved out of the inner face of the outer segment B². On each side are shown holes for strong screw-bolts, to connect the external series of sectional moulds with the interior ones, such as H². This shows the open window W and casing sunk in the mould, with corresponding holes, R, for the aforesaid binding-bolts. Q are square blocks cut out for the middle joists. Fig. 4 shows a separate piece, K, in which spaces are left for the joists on top of the upper sections. Fig. 3 shows the bolts R binding the segments B² H² and sections A² and I². N, a door-box. M, a box for the windows. J, the joists, projecting with a dove-tailed end; j, beyond the inner sections to within a short distance of the outer face. a shows a recess for the outer wall plate on the foundation. m is a piece of round or angled timber inserted at intervals vertically and centrally between the moulds. These are gradually raised as the composition is partially set, and leave open interstices between the moulds in the wall, both for ventilation and means of hastening the hardening, hereafter explained. D forms the cornice. A piece, e, is inserted between that and the upper flanges F to facilitate removing the moulds, said strip e having a slight bevel for the object named. With the sections all prepared and numbered, the lower series A¹, ², ³, and ⁴ are set up. The sections I¹, ², ³, ⁴, &c., behind them, the allotted distance apart. A vertical base-strip, G, is shown in sections, fig. 1; also a continuous binding-piece, E, on the lower flanges F, forming the lower front sections. These are continued around the sides and rear to form the lower story. The composition I find best adapted is formed out of the following materials in the proportions specified, which varies from other similar compositions: I take nine and a half pecks of clean sand to one peck of quicklime and two quarts of hydraulic lime or Roman cement; the lime and sand being intimately mixed and thoroughly digested, which may be promoted by enclosing the composition in a box and passing a jet of steam through it at various points. This has proved highly conducive for digesting the sand, and greatly reduces the time otherwise required to effect the same. This I do not claim as new, or a part of my invention, nor do I claim the composition or materials combined as new, although I differ in the proportions of the same from any I have yet met with. When properly digested, then

(the hydraulic lime being incorporated with the sand and lime) it is ready for filling and packing between the moulds, around the door, and window-boxes, projecting joists or timber, thoroughly driven into every portion of the moulds and stamped, (hydrostatic pressure may be employed as a means,) using the vertical timber *m* to form the tubular spaces, into which marble dust or broken limestones are thrown, when the timber is withdrawn and sulphuric acid poured in, and the top of the tube closed; this hastens the hardening of the cement or composition. Thus, when the lower segment moulds are filled, the second series are set up, their flanges bolted on, the binding-bolts *R* introduced, and the intervening spaces filled up, packed, and saturated with carbonic acid gas in like manner, up to the cornice and water-table, the joists inserted, and cross-framed as the walls go up. With the flooring, beams, &c., in place, supported in the moulds, for a cottage or central conic roof, the walls may be all of equal height, or gable ends can be set up in like manner by means of sectional moulds.

I am aware that houses have been put up by packing stiff mortar or cement between plan's, mixed with pebbles and fragments of stones, and boxing out the windows, gradually raising the planking as the walls harden and go up, or cutting out the openings for the windows after the mud or composition walls have been set up. What I deem novel in my mode of building consists in the use of two series of sectional moulds, with the box attachments for the doors and windows, the flanges and uniting screw-bolts, together with the arrangement of the dove-tailed projecting joists into the space between the moulds, the open spaces, and the introduction of carbonic acid gas in the manner specified; these, combined with my proportions of the materials, all acting conjointly as a means to a certain end, *i. e.*, the formation of compact, substantial walls, as durable as when made out of solid stone, neatly fashioned; and coming reasonably cheap, as one set of moulds will answer for many buildings, being easily set up and taken down, the holes of the bolts *R* filled up, and a final finish given in a manner never heretofore accomplished.

For ornamental walls around enclosures it is also very applicable, and deemed a novel and efficient mode of constructing houses. The composition may also be colored, of various shades, for cornice, window-caps, &c.

What I claim as my invention, and desire to secure by Letters Patent, is—

A series of sectional moulds, *A B*, for the outer face, and another, *H I*, for the inner face of walls, in combination with the door and window boxing *M N*, strips *K*, dove-tailed joists *J*; all arranged substantially and united by flanges *F* in the manner shown and specified.

In combination with my sectional moulds, I also claim the open interstices, when made for the admission of carbonic acid gas, for the purpose specified.

I also claim the proportions specified for making the composition, when introduced between sectional moulds, in the manner and for the purpose set forth.

JOHN R. RICHARDS.
